INVENTOR

UNITED STATES PATENT OFFICE

2,333,017

VACUUM CLEANER

Ward Leathers, Brooklyn, N. Y., assignor to Quadrex Corporation, New York, N. Y., a corporation of Delaware

Original application October 17, 1939, Serial No. 299,819. Divided and this application November 7, 1941, Serial No. 418,201.

4 Claims. (Cl. 230—132)

My invention pertains particularly to portable vertical-axis canister-type vacuum-cleaners of the type also shown in my co-pending applications for Letters Patent, Serial Nos. 299,819 and 209,909. This application is a division of application Serial No. 299,819, filed October 17, 1939, for Vertical axis canister type vacuum cleaner. An object of my invention is to reduce weight and bulk of the machine by disposing the motor-suction-unit within the inner portion of the filter and a large diameter single stage fan immediately above the filter; a further object being to obtain the highest suction volume ratio by means of the arrangement just mentioned together with a series of fixed reaction-blades closely shrouding the tips of the blades of the fan for reducing recirculation.

I have hereinafter set forth my invention so those familiar with these arts may understand it, and have appended drawing of which:

Figure 1 is a partially broken-away and a partially cross-sectioned view of my cleaner showing motor-suction-unit and deflector blades.

Figure 2 is a section of the ring of reaction blades which surrounds the fan of the motor-suction-unit.

A main shell 1 is disposed immediately above a dirt-receptacle 2 which has a connection 3 for the cleaning hose. Within the main shell 1 is a filtering mechanism 4 and motor-suction-unit 5. Above the shell 1 is a housing 6 which supports a bail-handle 7. A filter shaker handle 8 disposed on the side of the main shell 1 is held by a horizontal hinge 9 to an internal bow 10. The bow is trunnioned to a ring 11, both of which are preferably made of clock-spring-strip.

In order to provide ample space for large-capacity filter in a machine of minimum bulk (and weight) it is desirable to place the motor 5 within the cone apex 17 and to dispose the centrifugal fan for the same immediately above it. For high-capacity purposes I prefer to use a single-stage fan 20 of generous diameter in conjunction with a series of reaction blades 21, the object being that of obtaining far greater volume air-flow than with the conventional multiple stage compressors common to present-day horizontal-axis canister-type vacuum-cleaners. In order to obtain such a desirable arrangement I have devised means whereby the air from the clean side of the filter may be passed through the motor frame and thence into the eye of the fan. The fan has a substantially disc-like face at the outboard end of the motor drive shaft

and receives the air at a point between the blades and the motor. By this arrangement the motor is kept cool, the air is gotten into the fan with little resistance, and the widest diameter fan may be used consistent with a stepped-up E. M. F., thus obtaining a high-capacity performance without increasing bulk and weight.

Adjacent the tips of the fan 20 is a continuous ring of reaction or deflector blades 21. These may be provided, if desired, in sections, such as shown in Figure 2, and riveted to a cross plate 22 which has peripheral openings 23 for the free flow of air from the blower to the upper portion of the cleaner from which it is exhausted. These reaction blades are numerous and close together. They greatly reduce recirculation and thus greatly increase suction. Those familiar with these arts know that when the cleaning-nozzle is tightly held against a mapped surface the highest suction is desired, the highest being obtained by the multiple stage compressor. But when the nozzle is required to do more open cleaning the largest volume is desired, the highest being obtained with single-stage, high-tip-speed fan. Volume and suction being reciprocals of each other, and each being highly desirable on occasion, the present invention serves the important purpose of providing highly desirable characteristics for all kinds of cleaning at the end of the hose.

The invention is not to be limited to the exact arrangement of parts shown in the accompanying drawing or described in this specification as various changes in the details of construction may be resorted to without departing from the spirit of the invention. While the invention has been described in connection with a portable vertical axis canister type vacuum-cleaner, it is obvious that the same is applicable to horizontal axis type vacuum-cleaners. Thus, while throughout the specification and claims of this application reference has been made to a vertical axis vacuum-cleaner it is obvious that the entire unit comprising the present invention might well be turned upon its side so that the axis of the same extended in a horizontal direction. It is within the scope of the present invention to so modify the unit.

What I claim is:

1. In a vacuum-cleaner, a circular fan casing providing a fan chamber and having opposed central air inlet and outlet openings, a disc-and-blade fan mounted within the casing for rotation about the axis of the casing, said fan in-

cluding a substantially flat disc having a plurality of radially extending vanes extending outwardly therefrom, said casing being formed with a wall in close proximity to the outer radial edges of the vanes and substantially coextensive therewith, a fixed spider-like cross plate disposed in said chamber adjacent the disc and having air passages extending therethrough, and a plurality of deflector blades in the peripheral regions of said cross plate at spaced points therearound, said plates occupying substantially radial planes within the chamber and having their inner edges substantially coextensive with the outer edges of the vanes and positioned in close proximity thereto throughout the entire extent thereof.

2. In a vacuum-cleaner, a circular fan casing providing a fan chamber having a central air inlet at its bottom and an air outlet at its top, a disc-and-blade fan mounted within the casing for rotation about a vertical axis, said fan including a substantially flat disc having a plurality of radially extending vanes depending therefrom, said casing being provided with a downwardly sloping bottom wall in close proximity to the lower radial edges of the vanes and substantially coextensive therewith, a fixed spider-like cross plate disposed in said chamber immediately above the disc and having air passages extending therethrough and a ring-like deflector blade unit secured to said cross plate in the peripheral regions thereof and having a plurality of deflector blades depending therefrom, said deflector blades lying outside the circumferential sweep of said vanes and in close proximity to the outer edges of the said vanes and being substantially radially disposed in the chamber.

3. In a vacuum-cleaner, a circular fan casing providing a fan chamber having a central air inlet at its bottom and an air outlet, a disc-and-blade fan mounted for rotation within the casing about a vertical axis, said fan including a substantially flat disc having a plurality of radially extending vanes depending therefrom, said vanes projecting outwardly beyond the periphery

of the disc within the chamber, said casing being formed with a downwardly sloping bottom wall in close proximity to the lower radial edges of the vanes and substantially coextensive therewith, a fixed spider-like cross plate disposed in said casing immediately above the disc and having air passages extending therethrough, and a plurality of deflector blades depending from said cross plate in the peripheral regions thereof, said 10 blades occupying positions adjacent the periphery of said fan and being substantially radially disposed within the chamber, the inner edges of said blades being in close proximity to the sweep of the outer edges of said vanes, said 15 blades being relatively small and in close proximity to each other thus defining therebetween a relatively large number of small pressure chambers.

4. In a vacuum-cleaner, a circular fan casing providing a fan chamber having a central air inlet at its bottom and an air outlet, a disc-and-blade fan mounted for rotation within the casing about a vertical axis, said fan including a substantially flat disc having a plurality of radially extending vanes depending therefrom, said vanes projecting outwardly beyond the periphery of the disc within the chamber, said casing being formed with a downwardly sloping bottom wall in close proximity to the lower radial edges of the vanes and substantially coextensive therewith, a fixed spider-like cross plate disposed in said casing immediately above the disc and having air passages extending therethrough, a ring-like deflector blade unit secured to the peripheral regions of said cross plate, a plurality of outwardly struck deflector blades on said unit depending downwardly therefrom in close proximity to the outer edge of said disc, said blades being substantially radially disposed within the casing and having their inner edges arranged in close proximity to the circumferential sweep of said blades and defining relatively small pressure chambers therebetween.

WARD LEATHERS.
